UNITED STATES PATENT OFFICE.

EDWIN A. ROBBINS, OF BOSTON, MASSACHUSETTS.

CUFF-HOLDER.

SPECIFICATION forming part of Letters Patent No. 250,170, dated November 29, 1881.

Application filed May 26, 1881. (No model.)

To all whom it may concern:

Be it known that I, EDWIN A. ROBBINS, of Boston, in the county of Suffolk and State of Massachusetts, have invented certain new and 5 useful Improvements in Cuff-Holders, of which the following is a specification.

The object of my invention is to provide a cheap, simple, and convenient device for temporarily attaching, securing, and holding cuffs to the bindings or cuffs of shirt-sleeves, so as to permit the same to be adjusted as desired, to show more or less, when in use, below or beyond the end of the coat-sleeves, and also permit the said cuffs to be reversed and instantly 15 adjusted, or be removed therefrom when soiled or at any time when not desired; and it consists in the construction, combination, and arrangement of the pivoted clamping device or cam with the bent, flat, sheet-metal, double- 20 spring body portion provided with clips or ears and an opening, into and through which the said pivoted lever-cam operates, as hereinafter more fully described and set forth.

Figure 1 represents a perspective view of a 25 cuff-holder constructed according to my invention. Fig. 2 represents a longitudinal central section of the same when in use.

A represents a separate or "false" shirt-cuff, so called; and B represents a shirt wristband 30 or cuff attached permanently to the sleeve of the shirt.

C represents a cuff-holder, consisting of a flat sheet-metal body portion, one end of which is extended and bent into a bow-spring, D, leaving the free end E resting upon said body portion C, so as to form a spring-clamp for holding the cuff A when inserted between the said free end E and body portion C, which are of such length as to permit the cuff A to be adjusted therein longitudinally, as desired. The 35 opposite end of the holder is made to clamp upon the said shirt-wristband B, and for the

purpose is provided with a cam-lever, F, pivoted between the ears H H, and its holding end or edge J operates through an opening, K, 45 formed between the said ears H, and when closed or clamped upon the wristband B has a bearing opposite the inward-turned end, teeth, or edge of the short reverse-bent spring end L, which yields or springs sufficiently to adapt 50 the lever-clamp F J to the varying thicknesses of the wristbands or cuffs to which it may be desirable to temporarily attach the cuff-holder, as shown in Fig. 2.

It will be observed that the cam or clamp 55 end J when closed has a bearing slightly inward, or just beyond the inward-turned holding teeth or edge formed upon the end of the short spring L, whereby a more firm gripe or hold is obtained upon the wristband without 60 injury to the same.

The pivots are formed upon the edges of the sheet-metal lever-clamp or cam-holder F J, and are received into suitable holes formed in the ears H H when the same are bent up from 65 the sheet-metal body portion C, thus forming the cuff-holder from two pieces of sheet metal cut out of the form desired by means of suitable dies, and bent into the form shown, thus forming a cheap, simple, durable and convenient 70 cuff-holder.

Having thus described my invention, what I claim is—

In combination with the flat sheet-metal spring-clamp C D E, having ears H, opening 75 K, and flat spring-clamp L, the pivoted cam-lever or clamp F J, all being constructed and arranged substantially in the manner shown and described, as and for the purposes set forth.

EDWIN A. ROBBINS.
